United States Patent Office

Des. 196,764
Patented Oct. 29, 1963

196,764

BOAT

Gideon A. Kramer, Seattle, Wash., assignor to Hydro-Marine, Inc., Kirkland, Wash., a corporation of Washington

Filed Sept. 17, 1962, Ser. No. 71,737

Term of patent 14 years

(Cl. D71—1)

FIG. 1 is a view in side elevation of a boat showing my new design;

FIG. 2 is a view in front elevation thereof;

FIG. 3 is a view in rear elevation thereof; and

FIG. 4 is a top plan view thereof.

The dominant features of my new design are shown in full lines.

I claim:

The ornamental design for a boat, substantially as shown and described.
